UNITED STATES PATENT OFFICE

94,476

DESIGN FOR A WEDDING RING

Joseph Granat, San Francisco, Calif.

Application June 2, 1934, Serial No. 52,025

Term of patent 7 years

To all whom it may concern:

Be it known that I, Joseph Granat, a citizen of the United States of America, residing at San Francisco, county of San Francisco, and State of California, have invented a new, original, and ornamental Design for Wedding Rings, of which the following is a specification, reference being had to the accompanying drawing, forming a part thereof.

Fig. 1 is a plan view of a wedding ring showing my design, and

Fig. 2 is a perspective view thereof.

The circular elements disposed across the top of the ring indicate jewels. The general contour of the jewel mounting is concave on its side edges, these concavities extending to points adjacent the last jewels in both ends of the mounting as shown. The jewels in the mounting are small at the center thereof and are graduated to larger jewels at the ends of the mounting.

I claim:—

The ornamental design for a wedding ring substantially as shown and described.

JOSEPH GRANAT.
